UNITED STATES PATENT OFFICE

164,211

SPECTACLE FRAME

Egon F. Von Seekamm, New York, N. Y.

Application May 20, 1950, Serial No. 10,077

Term of patent 14 years

(Cl. D57—1)

To all whom it may concern:

Be it known that I, Egon F. Von Seekamm, a citizen of the United States and residing in the city, county and State of New York, have invented a new, original, and ornamental Design for a Spectacle Frame, of which the following is a specification, reference being had to the accompanying drawing, forming a part hereof and in which:

Fig. 1 is a front elevational view of a spectacle frame, showing my new design;

Fig. 2 is a side elevation of the same; and

Fig. 3 is a plan of the same.

My design for a spectacle frame is characterized by the particular type of ornamentation as seen most clearly in Fig. 1 combined with the placement of said ornamentation so as to leave the upper parts of the lens rims uneven because

of the position of the leaf-like elements constituting a part of said ornamentation.

I claim:

The ornamental design for a spectacle frame, as shown and described.

EGON F. VON SEEKAMM.
